UNITED STATES PATENT OFFICE.

GEORGE A. GILLEN, OF JERSEY CITY, NEW JERSEY, ASSIGNEE TO GILLEN, KIMMEL, BAKER SYNDICATE INC., OF ELMHURST, NEW YORK, A CORPORATION OF NEW YORK.

CONDENSER.

Application filed May 7, 1924. Serial No. 711,582.

This invention relates to improvements in variable condensers and its object is to provide a device wherein the positive and negative plates are relatively adjustable for both rough and fine adjustments.

Another object of the invention is to provide a variable condenser of the vernier type which differs from the ordinary type of vernier in that the fine adjustment is made with all of the plates and the provision of a separate and independently adjustable plate is rendered unnecessary.

A further object of the invention resides in the provision of a variable condenser so designed that its capacity may be accurately gauged without sacrificing in any way the full advantage of the vernier adjustment.

The above and other objects are attained by the construction, combination and arrangement of parts illustrated which while showing the preferred form of my invention is not to be deemed as limiting and I reserve the right to change the mountings, plates and other details to meet varying requirements without departing from my invention.

Figure 1, is a longitudinal sectional view through this condenser showing the same mounted upon a panel.

Figure 2, is a front end view of the condenser, showing the dials and panel removed.

Figure 3, is a rear end view of the condenser.

Figure 4, is a diagrammatic view showing the overlapping areas of the condenser plates, and

Figure 5, is a view similar to Figure 4 illustrating the adjustability of the plates.

Referring to the drawings in detail the numeral 16 designates the panel of an ordinary radio receiver or sending station upon which my improved condenser designated generically by the numeral 11 is mounted by means of screws 12.

The condenser 11 comprises a base plate 13 of insulating material such as "bakelite" or hard rubber and secured to the forward end of said base plate is a bracket 14 preferably of a metal stamping. This bracket is provided at its upper end with an opening formed with a rearwardly projecting collar 15 which forms a bearing for the adjusting shaft. Radiating arms 16 are formed on the bracket 14 and are pierced with threaded openings for the reception of the screws 12.

Threaded into the horizontal arms 17 formed on the bracket intermediate its upper and lower ends are guide rails 18, the rear ends of which are downturned as at 19 and secured to the base plate 13 adjacent its 60 rear end.

Slidably mounted on the guide rails 18 is a rear end plate 20 to which is fixed centrally an internally screw threaded sleeve 21 which projects forwardly therefrom to receive the threaded shaft 22 which projects rearwardly from the bracket 14 as clearly shown in Figure 1.

This threaded shaft is mounted for rotation in the sleeve 23 which in turn is rotatably mounted in the collar 15, and both the sleeve 23 and shaft 22 are projected forwardly through the panel 16 to receive the knob 24 and dial 25 respectively.

Fitted on the rear end of the sleeve 23 is a 75 collar 26 carrying a substantially fan-shaped plate 27 which is provided on its rear face with a series of concentric semi-circular grooves for the reception of the rotor plates 28 which are adapted to be received between 80 the stator plates 29 which are in turn mounted in concentric grooves formed in the front face of a substantially fan shaped plate 30 carried on the rear end plate 20. This plate is cut out as at 31 to avoid contact with the 85 sleeve 21 and depending from said plate is a contact arm to which a binding post 32 is connected.

Secured to the plate 13 are the stationary binding posts 33 and 34, which are respectively connected by conductors 35 and 36 to the binding post 32 and the end 37 of the sleeve 21.

In operation, the rough adjustment between the plates is secured by rotating the 90 dial 25 which in turn rotates the rotor plates, relative to the stator plates. Finer adjustments are then secured by rotation of the knob 24 which through the medium of the threaded shaft and the sleeve causes the 100 rear end plate 20 to move inwardly or outwardly according to the direction of rotation. Obviously the latter adjustment can be more readily controlled and extremely fine adjustments may be made.

While in the foregoing there has been shown and described the preferred embodiment of this invention, it is to be understood that minor changes in the details of construction, combination and arrangement of 110

part may be resorted to without departing from the spirit and scope of the invention as claimed.

What is claimed is:-

- 5 A condenser comprising a base, spaced parallel guide bars on the base, a rear end plate slideable on the guide bars, transversely arcuate plates carried on the forward face of the rear end plate, a screw for adjusting 10 the end plate longitudinally of the base, a bracket at the forward end of the base, a sleeve rotatable through the bracket, a fan

shaped plate at the inner end of the sleeve, transversely arcuate plates extending rearwardly from the fan shaped plate and 15 adapted to enter the spaces between first named arcuate plates, means for rotating the sleeve, and independent means for rotating the screw whereby the plates may be relatively adjusted. 20

In testimony whereof I have signed my name to this application.

GEORGE A. GILLEN.
